Primary Examiner — Mojtaba Tehrani(74) *Attorney, Agent, or Firm* — Andrzej Malarz, Esq.(57) **CLAIM**

The ornamental design for a gun sight as shown and described.

DESCRIPTION

FIG. 1 is an exploded front, top, right side, perspective view of a gun sight showing our new design;

FIG. 2 is a rear top left side perspective view thereof;

FIG. 3 is a left side elevation view thereof; a right side elevation view is a mirror image thereof;

FIG. 4 is a front elevation view thereof; and,

FIG. 5 is a rear elevation view thereof.

The broken line in the drawings disclose the unclaimed portions of the gun sight only and forms no part of the claimed design.
